UNITED STATES PATENT OFFICE.

WILLIAM H. BANZETT, OF BERGENFIELD, NEW JERSEY, ASSIGNOR TO AMERICAN LITHOGRAPHIC COMPANY, OF NEW YORK, N. Y., A CORPORATION OF NEW YORK.

PLATE-REGISTERING MECHANISM.

1,370,624.

Specification of Letters Patent.

Patented Mar. 8, 1921.

Application filed July 23, 1919. Serial No. 312,813.

To all whom it may concern:

Be it known that I, WILLIAM H. BANZETT, a citizen of the United States, and a resident of Bergenfield, in the county of Bergen and State of New Jersey, have invented 5 certain new and useful Improvements in Plate-Registering Mechanisms, of which the following is a specification.

This invention relates to plate registering 10 mechanisms for printing presses. The object of my improvements is to provide mechanism of the class specified, of simple construction, and which can be readily manipulated and accurately adjusted for bringing 15 a plate on one cylinder or platen into close register with a similar plate on another cylinder or platen. To these ends my improvements comprise features illustrated in their preferred embodiment in the drawings 20 accompanying this specification, wherein:—

Figure 1 is a diagrammatic side elevation of the essential elements of a multi-cylinder rotary printing press. Fig. 2 is a plan view of one of the plate holding means for a 25 cylinder. Fig. 3 is a cross-sectional elevation on line 3—3 of Fig. 2. Fig. 4 is a plan view of another of the plate holding means for a cylinder. Fig. 5 is an end elevation of 30 what is shown in Fig. 4. Fig. 6 is a cross-sectional elevation on line 6—6 of Fig. 4. Fig. 7 is an end elevation of a plate clamping and tensioning means of well known 35 character. The drawings are all to one scale.

Referring now particularly to Fig. 1, impression cylinder 2 has adjacent thereto and for coaction therewith a plurality of form cylinders 7, 8 and 9 and which cylinders are provided with design bearing plates 4, 5 40 and 10, respectively. Said form cylinders 7, 8 and 9 are provided with the usual inking mechanisms as 11 to cylinder 7. Also, said design bearing plates 4, 5 and 10 may be adapted for printing in a plurality of 45 colors, all contributing to the printing on a sheet carried by cylinder 2 of a design of predetermined character. In any case it is required that the impressions from the several cylinders 7, 8 and 9 on the sheet 50 carried by cylinder 2, shall be in accurate register. Approximate register is easily attained by a variety of well known means, but the final adjustment of the several design plates on the several cylinders, respectively, into highly accurate adjustment has

heretofore been attended not only with difficulty but has been attained only after more or less protracted experimentation, which consumes time and patience and is attended by wasteful making of proofs. By my improvements the plates may be set in primary approximate register of great accuracy and the final adjustment of such minute differences as remain may be made with promptness and precision.

To this end I attach to one end of each of the several plates which are to be brought into register on the cylinders, a bar in predetermined relation to the design on the plate, lengthwise, crosswise and angularly thereof. Said bar for convenience may comprise two members 12 and 13 between which the end of the plate, as plate 4, is clamped. This bar may be fixed to said plate before the design is applied to the plate and may be used as a gage for locating the design on the plate, or, it may be attached after the design is applied. In cylinder 7 there is provided fixed holding block 14 having a seat for the reception and accurate location of bar 12, 13 and clamp members 15 for securing said bar in place on its seat. Also said bar 12, 13 is located endwise block 14 by stops 16, 17. The other end of said plate 4 may be tensioned to draw the plate snugly to the cylinder by some well known means such as shown in Fig. 7. On cylinder 8, plate 5, which is also provided at one end with bar 12, 13 similar to bar 12, 13 of plate 4, may be provided at its other end with a similar bar 12, 13. These bars 12, 13 on opposite ends of plate 5 are mounted in seats and clamped in place in opposite holding blocks 18, 18 somewhat similar to block 14 but differentiated by the fact that blocks 18 are pivotally mounted on bolt 19 midway their lengths in cylinder 8. For angularly adjusting said blocks push screws 20, 20 abutting against wall 21 of said cylinder are employed. For adjusting bars 12, 13 a minute distance circumferentially of the cylinder and relatively to block 18, wedges 22, 23 may be employed. For adjusting bars 12, 13 lengthwise block 18 and cylinder 8, opposite angular arms 24, 25 pivoted at 26, 27 respectively on block 18, are provided. One end of each of said arms bears against one end respectively of bar 12, 13 and the other end is provided with push screw 28 impinging against a wall of block 18. Thus

by means of the features just described bars 12, 13 and plate 5 to which they are attached may be adjusted lengthwise, crosswise and angularly, relatively to said cylinder 8, to 5 bring plate 5 on said cylinder into accurate register with plate 4 on cylinder 7. Additional cylinders, as 9, are similarly equipped whereby their plates, as plate 10 on cylinder 9, may be brought into accurate 10 register with the plates on the preceding cylinders.

I claim:

1. In plate adjusting means, the combination of a block, a plate having a bar attached to an end thereof, a seat in said block for said bar, and means for adjusting said bar lengthwise said block comprising a pivoted arm, one end of said arm bearing against an end of said bar and the other 15 end of said arm being provided with an adjusting screw for engagement with said block.

2. In plate adjusting means, the combination of a block, a plate having a bar

attached to an end thereof, a seat in said 25 block for said bar, means for adjusting said bar transversely said block comprising a wedge between said bar and block, and means for adjusting said bar lengthwise said block comprising a pivoted arm, one end of 30 said arm bearing against an end of said bar and the other end of said arm being provided with an adjusting screw for engagement with said block.

3. In plate adjusting means, the combination of a cylinder, a block pivotally mounted on said cylinder, means for swiveling said block on its pivot, a plate having a bar attached to an end thereof, a seat in said block for said bar, means for adjusting said 35 bar transversely said block, and means for adjusting said bar lengthwise said block.

In witness whereof, I hereby affix my signature this 12th day of July, 1919.

WILLIAM H. BANZETT.
